(57) **CLAIM**

The ornamental design for a bottle, as shown and described.

DESCRIPTION

FIG. 1 is a perspective view of a bottle illustrating my new design.

FIG. 2 is a rear perspective view of the bottle in FIG. 1; and, FIG. 3 is a top view of the bottle in FIG. 1.

Broken lines are included for the purpose of illustrating environmental structure and form no part of the currently claimed design.
